UNITED STATES PATENT OFFICE.

LUTHER L. KNOX, OF BEN AVON, PENNSYLVANIA.

FURNACE-DOOR FRAME.

No. 910,925.

Specification of Letters Patent.

Patented Jan. 26, 1909.

Application filed June 30, 1908. Serial No. 441,179.

To all whom it may concern:

Be it known that I, LUTHER L. KNOX, of Ben Avon, Allegheny county, Pennsylvania, have invented a new and useful Improvement 5 in Furnace-Door Frames, of which the following is a full, clear, and exact description, reference being had to the accompanying drawings, forming part of this specification, in which—

10 Figure 1 is a front elevation of one form of door frame embodying my invention; Fig. 2 is a vertical section on the line II—II of Fig. 1; Figs. 3, 4 and 5 are similar sections showing modified forms of the invention; Fig. 6 is 15 a front elevation of another form of the invention; and Fig. 7 is a section on the line VII—VII of Fig. 6; Fig. 8 is a section on the line VIII—VIII of Fig. 6; and Fig. 9 is a front elevation of still another form of the invention; Fig. 10 is a section on the line X—X 20 of Fig. 9; and Fig. 11 is a plan view of the form shown in Figs. 9 and 10.

My invention has relation to furnace door frames, and particularly to frames of the 25 general character described and claimed in my Patent No. 864,752, dated August 27th, 1907. The frame described in that patent consists of a main frame provided with a door opening therein, and a supplemental frame 30 member arranged to fit within the said opening to form a surrounding rim therefor, either wholly or in part, means being provided for circulating a cooling fluid within the supplemental member. This supplemental frame 35 member constitutes that portion of the frame which is most subject to the destructive heat of the furnace, and is so arranged that it may be readily removed and replaced when burned out; and since this frame forms but 40 a comparatively small part of the door frame as a whole, this renewal and replacement can be effected at a comparatively small cost and without dismantling the furnace.

The present invention relates more particularly to the construction of this supplemental frame, whereby it is provided with 45 means for supporting an arch of refractory material, said arch constituting a portion of the upper wall of the door opening into the 50 furnace.

A further object of the invention is to provide this supplemental frame with a detachable top or lintel portion which can be removed and replaced by itself and independently of the supplemental frame as a whole. 55

The precise nature of my invention will be best understood by reference to the accompanying drawings, in which I have shown several embodiments thereof, and which will now be described, it being premised, however, that it is susceptible of various other modifications by those skilled in the art without departing from the spirit and scope of the invention as defined in the appended claims.

Referring first to the form of the invention shown in Figs. 1 and 2, the numeral 2 designates the main metallic member of the door frame, which is here shown as of substantially the same construction as in my said patent above referred to. 3 is the supplemental frame, which, as in the said patent, consists of a rim-like hollow structure, which is adapted to fit within the door opening 4 of the main frame, and is detachably secured to said 75 main frame by any suitable means such as the lugs 5 at its lateral edges, which engage recesses 6 in the main frame, and are held therein by means of suitable keys 7. 8 designate connections, whereby a cooling fluid may 80 be circulated through the supplemental frame. Any suitable arrangement of baffling may be provided within the supplemental frame for effecting a proper circulation of water therein. In accordance with my present invention, the upper portion of this supplemental frame is provided with the skew-backs 9, which support the arch 10 of refractory material which forms a lining for the top 85 or lintel portion of the supplemental frame 90 and which forms a continuation of the brick-work arch over the door opening through the furnace wall. By providing the top or lintel portion of the supplemental frame with these skew-backs, a refractory lining can be provided therefor which protects the frame from destruction, and which is itself protected by the cooling action of the frame, this refractory lining being furthermore readily removable and replaceable, either with or independently of the supplemental frame. 95

The construction shown in Fig. 3 differs from that shown in Figs. 1 and 2, in that the top or lintel portion 11 of the supplemental frame is made as a separate piece and is of approximately L-shape in cross-section, having the extension 12 which projects inwardly into the wall of the furnace, and which is provided with skew-backs which support the refractory lining 13. It will be noted that 110

this refractory lining does not extend entirely to the front of the furnace, but that the skew-backs are carried by the inwardly projecting portion 12. The separate top or lintel 11 has detachable circulating connections 14 with the side legs of the table frame.

Fig. 4 shows another form of the supplemental frame, in which the top or lintel portion 15 is also made detachable, but in this case the skew-backs which support the refractory lining 16 extend entirely to the front of the frame.

The form shown in Fig. 5 is similar to that shown in Fig. 3, except that the frame is of slightly different cross-section so as to carry a straight-walled arch lining instead of an upwardly and inwardly inclined arch as shown in Fig. 3. The top or lintel portion of the frame is in this form made in one piece 20 with the leg portions.

Figs. 6, 7 and 8 show a construction similar to that of Fig. 4, except that the skew-backs on the removable top or lintel section 17 are omitted. This top or lintel portion is also shown as being provided with a plurality of interior baffles 18 for effecting a back and forth water circulation therethrough. The circulating pipes 19 instead of being brought out at the center of the main frame, 25 as in the forms before described, are brought out one at each side portion of the main frame in recesses between the flanges 20, over which the usual door is arranged to slide. In this form the side legs 21 are 30 shown as having the outward extensions 22, which fit over the side legs of the main frame in the manner shown in Fig. 8.

In the form shown in Figs. 9, 10 and 11, the top or lintel portion of the supplemental 40 frame is formed integrally with the side legs, and consists of two portions 23 and 24, the portion 23 being offset inwardly with respect to the portion 24, and into the brick wall, and having skew-backs 25 which support the refractory lining arch 26.

It will be understood that in any of the different forms of my invention which I have shown, the top or lintel portion may be either detachable or in one piece with the 50 side portions. It will also be noted that in the form shown on sheet 2, the side legs of the supplemental frame are not connected at the bottom, as in the other form. This bottom leg or connection may or may not be 55 used with any of the several forms shown.

The advantages of my invention will be readily appreciated by those familiar with this art, since it provides a door frame in which the parts which are most subject to 60 the destructive action of the heat from the furnace can be readily renewed and replaced without disturbing the door frame as a whole, and at a comparatively slight cost.

By providing the top or lintel portion of 65 the supplemental frame with skew-backs for

supporting the arch or lining, if the brick work at the sides of the door-opening becomes burned out or destroyed, the supports for the arch or lining formed by the skew-backs remains intact.

70

I claim:—

1. A furnace door frame consisting of a main frame member, and a separate supplemental or rim frame member removably fitting within the door opening of the main member and having a top or lintel portion formed separately from its side legs; substantially as described.

75

2. A furnace door frame consisting of a main metallic member having a door opening therein, and a separate supplemental frame member removably fitting within said door opening and consisting of a hollow rim-like structure, said supplemental frame member having its top or lintel portion 80 formed in a separate piece, and means for circulating a cooling fluid through said supplemental member; substantially as described.

85

3. A furnace door frame consisting of a main member having a door opening therein, and a supplemental member in the form of a rim-like structure arranged to fit within the opening in the main frame member, and having skew-backs at its upper portion for supporting an arch or lining of refractory material; substantially as described.

95

4. A furnace door frame consisting of a main frame member having a door opening therein, and a supplemental frame member in the form of a hollow rim-like structure arranged to fit within said opening and to extend inwardly into the wall of the furnace and to be detachably secured to the main frame member, and an arch or lining of refractory material carried by the supplemental frame member; substantially as described.

100

5. A furnace door frame consisting of a main frame member having a door opening therethrough, and a supplemental frame member fitting within said opening and detachably secured to the main frame member, said supplemental frame member having a portion extending inwardly into the furnace wall and provided with means for supporting 110 an arch or lining of refractory material, and means for circulating a cooling fluid through the supplemental frame member; substantially as described.

115

6. A furnace door frame having skew-backs, and a refractory arch or lining carried by said skew-backs and supported thereby independently of the adjacent brick work of the furnace; substantially as described.

120

In testimony whereof, I have hereunto set 125 my hand.

LUTHER L. KNOX.
